(57) **CLAIM**

The ornamental design for a car ramp assembly, shown and described.

DESCRIPTION

FIG. 1 is a perspective view of a car ramp assembly showing my new design, shown assembled;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing one portion of the car ramp assembly;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is another bottom view thereof;

FIG. 15 is a perspective view showing the other portion of the car ramp assembly;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The portions of the car ramp are shown separated in FIG. 8 through FIG. 21. The broken line portions of the car ramp assembly in FIGS. 1-21 represent unclaimed portions of the claimed design and form no part thereof. The clot-dash broken lines in FIGS. 1, 4-5, 8, 11-12, 15 and 18-19 represent unclaimed boundary lines and form no part of the claimed design.
